CALIFORNIA.

PISTON HEAD FOR PUMPS.

1,411,792.

Specification of Letters Patent. Patented Apr. 4, 1922.

Application filed June 10, 1920. Serial No. 388,028.

To all whom it may concern:

Be it known that we, CHARLES E. McGEE and JERRY M. KENT, citizens of the United States, residing at Santa Monica, county of Los Angeles, State of California, and Los Angeles, county of Los Angeles, State of California, have invented a new and useful Improvement in Piston Heads for Pumps, of which the following is a specification.

10 My invention relates to lift pumps such as those commonly used in oil wells, in which the pump is placed near the bottom of the oil tubing, being operated from a beam in the derrick by means of a line of sucker rods 15 passing downwardly through the tubing.

Such pumps commonly consist of a working barrel in which a piston is reciprocated. Such pumps especially where some sand is found in the well are difficult to keep tight, 20 the working barrel and piston rapidly wearing. It is an expensive and troublesome matter to remove such pumps for repair especially where the working barrel must be removed as this involves pulling the tubing from the well.

It is common practice at the present time to construct said pumps with a long piston which is made an accurate fit in the working barrel, no piston rings or packing being 30 used, the efficiency of the pump depending solely on the accuracy of the fit between the long cylindrical plunger and the working barrel in which it is reciprocated. Such pumps are very efficient when new but once 35 the accuracy of this fit is impaired, the pumps deteriorate very rapidly and the pistons and linings of the working barrels must be replaced. This is expensive not only on account of the cost of the new parts 40 but also on account of the expense of removing the pump from the well, and the loss in oil production during the time required for this removal and replacement.

It is an object of our invention to provide 45 an oil well pump which is provided with flexible packing which is carried on the piston and which may be tightened up from time to time to compensate for wear.

It is a further object of our invention to 50 provide a structure in which the packing may be tightened up without removing any parts from the well.

It is a further object of our invention to 55 provide a pump having such flexible packing in which the packing may be carried in an

unexpanded condition on the piston so that the piston may be lowered into the well and which is further so constructed that this packing may be expanded in place in the working barrel. 60

Further objects and advantages will be made evident hereinafter.

Referring to the drawing which is for illustrative purposes only,

Fig. 1 is a view of a portion of a pump 65 equipped with my invention.

Fig. 2 is a similar view on a smaller scale, and

Fig. 3 is a section on the line B—B of Fig. 1. 70

In the form of my invention illustrated in these drawings, 21 is the working barrel of the pump which is threaded at its upper end for attachment to the tubing, not shown. Threaded on the lower end of the working barrel 21 is a coupling or working barrel shoe 29 which provides a tapered seat for the standing valve seat 28. Resting on a seat ring 27 carried in the seat 28 is the standing valve ball 26 which is placed inside 80 a cage 22 which is threaded to the member 28. Threaded in the cage 22 is a garbutt rod 19 which may be square and provided with oil grooves 19' as shown in Fig. 3.

The rod 19 passes through a square hole in 85 a piston follower 2 which is of such size that the rod 19 and the piston follower turn together although the piston follower can freely slide vertically on said rod. The piston follower 2 is threaded in a piston 6. 90 Nuts 5 and 3 are placed on the follower 2 as shown in Fig. 1 and elastic packing 4 is compressed therebetween whenever the follower 2 and the piston 6 are screwed together. The rod 19 extends through the piston 6 into 95 a tube 20 without engaging either so that the piston 6 and the tube 20 can turn freely about the rod 19. A nut 18 on the top of the rod 19 is, however, of such size that it cannot pass through the opening in the piston 6 so that when the piston 6 is withdrawn from the well, the rod 19, the cage 22 and the seat 28 are all withdrawn also. 100

Threaded to the tube 20 is a working valve cage 24 containing the working valve 23 105 which rests upon a seat ring 25. The pump rods 17 are secured to the cage 24.

The method of operation of my invention is as follows:

The packing 4 being wrapped around the 110

stem 13 of the follower 2 but only slightly compressed, the piston 6 with the standing valve, and its parts, dependent therefrom on the rod 19 is lowered into the well, the standing valve seat dropping into the member 29. The piston 6 can now be reciprocated by the pump rods 17. If the packing 4 is too loose, the pump rods 17 are turned, thus turning the piston 6. The follower 2 being held from rotation by the rod 19 is screwed up into the piston 6, thus compressing and expanding the packing 4. Whenever the packing 4 wears, it can again be expanded by turning the pump rods 17.

15 We claim as our invention:

1. In a pump, the combination of: a cylinder; a piston sliding in said cylinder; a follower threaded to said piston; packing carried between said piston and said follower and expanded thereby; constantly engaged means for preventing the rotation of said follower in said cylinder; and means for rotating said piston in said cylinder.

2. In a pump, the combination of: a cylinder; a piston sliding in said cylinder; a follower threaded to said piston; packing carried between said piston and said follower and expanded thereby; constantly engaged means for preventing the rotation of said follower in said cylinder; and an operating rod secured to said piston and suited to reciprocate and rotate same.

3. In an oil well pump, the combination

of: a working barrel; a piston sliding in said barrel; a follower threaded in said piston; packing expanded by said follower and said piston; a standing valve structure; a garbutt rod attached to said standing valve structure and engaging said follower and preventing the rotation thereof; and pump rods by which said piston may be rotated.

4. In an oil well pump, the combination of: a working barrel; a piston sliding in said barrel; a follower threaded in said piston; packing expanded by said follower and said piston; a standing valve structure; a garbutt rod attached to said standing valve structure and engaging said follower and preventing the rotation thereof; and pump rods rigidly secured to said piston.

5. In an oil well pump, the combination of: a working barrel; a piston sliding in said barrel; a follower threaded in said piston; packing expanded by said follower and said piston; constantly engaged means for preventing the rotation of said follower in said working barrel; and pump rods rigidly secured to said piston.

In witness that we claim the foregoing, we have hereunto subscribed our names this 8th day of May, 1920.

CHARLES E. McGEE.
JERRY M. KENT.
